UNITED STATES PATENT OFFICE.

JAMES E. GLEASON AND ALTON P. SLADE, OF ROCHESTER, NEW YORK, ASSIGNEES TO
GLEASON WORKS, OF ROCHESTER, NEW YORK, A CORPORATION OF NEW YORK.

APPARATUS FOR FINISHING CURVED-TOOTH GEARS.

Application filed March 24, 1923. Serial No. 627,464.

This invention relates to an apparatus for finishing curved tooth gears, or what are sometimes called "spiral" gears, in which the teeth are curved lengthwise across the face 5 of the gear.

A principal purpose of the invention is to provide for finishing the surfaces of gear teeth by grinding, after they have been cut and hardened, whereby they will have accurately finished and smooth running profiles.

An additional object of the improvement is to afford a practical and efficient mechanism that will finish a gear correctly and in the quickest possible manner, removing 15 any irregularities in the surface of the teeth that may be caused during the hardening process.

With these ends in view, the invention includes the principles and mechanism that will appear clearly from the following description when read in conjunction with the accompanying drawings, the novel features being pointed out in the claim following the 25 specification.

In the drawings:

Figure 1 is plan view, partly in horizontal section, of a machine embodying a practical adaptation of the invention;

30 Figure 2 is an enlarged plan view of the dressing mechanism for the grinding member, the latter being broken away;

Figure 3 is a side elevation of the structure appearing in Figure 2;

35 Figure 4 is a sectional view on the line 4-4 of Figure 2;

Figure 5 is a sectional view on the line 5-5 of Figure 2, and

40 Figure 6 is a plan view of the gear blank and grinding member in operative relationship.

The invention is intended principally for finishing gears of the general type constructed by the mechanism illustrated in Patent No. 1,203,608, November 7, 1916, or what are known as curved or spiral tooth gears, and while the present disclosure has to do more particularly with bevel gears, the invention in its broader aspect is applicable 50 equally to bevel or spur gears, where the teeth are curved lengthwise across the face of the gear.

In general the invention includes a grinding member constructed of suitable abrasive material including an annular gear engag-

ing and grinding portion which travels through a tooth space of the gear blank as the grinding member is rotated. The mechanism and principle now to be described may be carried out by operating 60 on one or two tooth faces at a time by using either one or both curved faces of the grinding member, and the grinding member may be either of the male type, in which case it travels in a tooth space between 65 adjacent teeth, or of the female type in which case it may straddle a tooth and operate simultaneously on opposite faces of a single tooth. In order to illustrate a practical embodiment as an example of the invention, this application discloses a structure comprising a bed 1 having suitable curved guideways in its base in which is mounted a grinder cradle 2 for oscillatory rolling or generating motion, while 3 designates generally a gear blank support also arranged on the base 1 and mounted for oscillatory motion about its longitudinal axis so as to permit the necessary relative generating motion between the gear blank and grinding member corresponding to the relative movement of the gear blank on a crown gear, one tooth of which is represented by the grinding element.

The mechanism for supporting and operating the cradle 2 and the blank support 3, to obtain the proper coaction between the gear blank and grinder cradle 2, is the same as in the patent above referred to, or may be of other convenient form, and since these 85 motions are well known in the gear generating art and the details of the mechanism for effecting such motions form no part of this invention, it is unnecessary to make any further disclosure. By referring to the 90 above mentioned patent, all parts and movements necessary to effect proper operation of the blank support and grinder cradle will be found.

This invention has to do with the application to the cradle 2 of a grinding member, which has a gear engaging and grinding portion 4 of annular or face mill form. The grinding member also includes a body or base portion by which it is suitably mounted 100 on a spindle 5 which carries a pulley 6 to which power may be supplied from any suitable source.

The annular portion 4 is illustrated, see 105 Figure 2, as having converging grinding

faces, which may operate simultaneously on opposite space bounding faces, or the grinding member may be employed to operate only on one tooth face at a time, as desired, and 5 while the grinding member herein disclosed is of the male type for operation in a tooth space, the invention may be adapted to simultaneously completing opposite faces of a single tooth at once by means of a female 10 grinding member. The mechanism and cycle of movements involved in moving the blank into operative relationship with the grinding member, effecting a relative generating or rolling motion between the gear 15 and grinding member, withdrawing said parts one from the other, and thereafter indexing the gear to bring another tooth space into operative position, are the same as set forth in the patent previously referred 20 to.

In the preferred operation, according to the present invention, we take a completed gear blank, after it has been cut and heat treated for hardening, and place it on the 25 machine so that the annular portion 4 of the grinding member is located within a tooth space. The grinding member is rotated continuously, and during such rotative action it is traversed back and forth 30 by the oscillatory cradle 2 with reference to the gear, which at the same time is oscillated about its own axis, and in this manner the proper shape is imparted to the profile of the tooth. Between successive grinding 35 operations, the blank and grinding member are disengaged and the blank indexed to present another portion thereof to the grinding member, as usual in gear generating machinery.

40 The grinding member is dressed by the mechanism that will now be described. Attached to a stationary portion of the frame or cradle on which the grinding spindle 5 is mounted, is a bracket 7 having an arm 45 or extension 8 at its outer end, provided with a circular groove 9, and 10 is a bracket adjustably mounted on the arm 8 by means of a tongue 11 engaging said groove 9 and bolts or other suitable fastening means by

which the bracket 10 is secured to the arm 50 8 in adjusted position.

The bracket 10 includes a pair of guides 12, in the form of walls arranged parallel respectively to the opposite faces of the annular portion 4 of the grinding member. 55 13 is a carrier upon which the diamond dresser 14 may be mounted, so as to contact with the operative surface of the grinding member and by moving the carrier 13 back and forth on the bracket 10, in contact with the guide 12, the dressing tool is moved across the operative face of the grinding member in contact therewith to keep it true. The carrier 13 may be operated either by hand or suitable automatic mechanism provided for the purpose. 60 65

While the invention has been described with reference to certain structural embodiments, it is not confined to the particular mechanism or arrangement herein set forth, 70 and this application is intended to cover any modifications or adaptations of the apparatus described, that come within the intended purpose of the improvements or the scope of the following claim.

We claim:

An automatic machine for accurately finishing the working surfaces of spiral bevel gears comprising a bevel gear blank support, a rotary annular grinding member including an enlarged base or body portion and a reduced grinding portion, said reduced grinding portion having converging and uninterrupted grinding surfaces affording a rack tooth formation in cross-section and of circular curvature conforming to the lengthwise curvature of the gear teeth and movable through a curved portion between adjacent teeth, and an oscillatory carrier on which one of said elements is mounted to produce a relative generating movement between the grinding member and bevel gear blank. 85

In witness whereof, we have hereunto signed our names.

JAMES E. GLEASON.
ALTON P. SLADE.
